United States Patent Office

Des. 206,603

Patented Jan. 3, 1967

206,603

PULL TOY OR SIMILAR ARTICLE

William D. Elzaurdia, Deerfield, and Wesley E. Sharer,
Chicago, Ill., assignors to Playskool Manufacturing
Company, Chicago, Ill., a corporation of Illinois

Filed Nov. 8, 1965, Ser. No. 88,043

Term of patent 14 years

(Cl. D34—15)

Fig. 4

FIG. 2 is a front perspective view;

FIG. 3 is a top perspective view;

FIG. 4 is a bottom perspective view;

FIG. 5 is a rear perspective view; and

FIG. 6 is a side elevational view wherein the hat has been omitted.

The dominant features of the design reside in the portions shown in full lines.

We claim:

The ornamental design for a pull toy or similar article, as shown and described.
